Primary Examiner—Dominic Simone(74) *Attorney, Agent, or Firm*—Goodwin Procter LLP(57) **CLAIM**

The ornamental design for a shoe, as shown and described.

DESCRIPTION

FIG. 1 is a front perspective view of the shoe;
 FIG. 2 is a rear medial side perspective view of the shoe;
 FIG. 3 is a front medial side perspective view of the shoe;
 FIG. 4 is a front lateral side perspective view of the shoe;
 and,
 FIG. 5 is a bottom view of the shoe.

The shoe shown in FIGS. 1-5 is a left shoe. The right shoe is a mirror image of the left shoe. Elements of the shoe shown in uneven broken lines are for illustrative purposes only and form no part of the claimed design.
